ART OF SEPARATING MIXED GASES

William L. De Baufre, Orange, N. J.

Application June 16, 1931, Serial No. 544,733

3 Claims. (Cl. 62—123)

This invention relates to improvements in the art of separating mixed gases and is especially useful in the production of oxygen and/or nitrogen, either or both in a relatively pure state.

5 One of the primary objects of the invention is to facilitate the starting and the operation of the system. In connection with this it is of particular advantage where there is no predrying of the air so that in starting up, instead of the moisture being carried over in other parts of the apparatus, the interchangers are gotten down quickly to operating temperature so that the moisture is frozen out before it is carried over.

10 Another advantage of the arrangement is that the operation of the system may be varied within limits to suit particular conditions.

15 I accomplish the foregoing, together with such other objects and advantages as may hereinafter appear, or are incident to the invention, by means 20 of an arrangement which is illustrated in the preferred form in the accompanying drawing, the figure being a diagrammatic view partly in side elevation and partly in section illustrating the preferred embodiment of the invention.

25 Referring now to the drawing the air separation plant comprises two interchangers A and B, a liquefier C, an expansion engine D, two exchangers K and L, a purifier M and a rectifying column made up of a pot E, a preliminary tray 30 section F, a vaporizer section G, a main tray section H and a top tube section J.

35 Air compressed to the necessary operating pressure, say 500 lb. gage, enters the system at the air inlet 1 at, say, 30 centigrade. This compressed air is nearly free of carbon dioxide which has been removed in purification apparatus not shown. The compressed air is saturated with water vapor, however, and contains oil vapors from the lubricant used in the compressor.

40 With valves 2, 5 and 7 open, and valves 3, 4 and 6 closed, the compressed air passes up around the tubes in interchanger A and then up around the tubes in interchanger B, leaving the latter through pipe 8. Valves 9, 10 and 11 should be closed and 45 valves 12, 13 and 14 open. Then the oxygen and nitrogen separated in the rectifying column will be returning through interchanger B and not through interchanger A. If the valves 2, 3, 4, 5, 6, 7, 9, 10, 11, 12, 13 and 14 have just been reversed, 50 interchanger A will be cold and the compressed air will be more or less cooled therein by warming up the interchanger and thawing out the accumulated ice. After the ice is completely thawed out and interchanger A warmed up, the compressed air will not be appreciably cooled therein,

but will enter interchanger B at about 30 centigrade. In interchanger B the compressed air will be cooled by the returning oxygen and nitrogen flowing through the tubes therein to, say, minus 110° centigrade.

55 After leaving the interchangers through pipe 8, the compressed air divides, part going through pipe 15 to the liquefier C, while the larger portion passes to expansion engine D through pipe 16. The portion entering the liquefier is liquefied 60 therein by the returning oxygen and nitrogen from the rectifying column, the level of the accumulated air being indicated on level gage 17. The portion of the compressed air passing to expansion engine D is expanded therein to, say, 75 lb. gage 65 and from thence passes through pipe 18 to the lower end of the preliminary tray section F.

70 The preliminary tray section F contains a number of trays arranged to cause the rising vapor from the expansion engine to bubble through liquid which is flowing down from tray to tray. With a single acting expansion engine as indicated in the figure, it was found that the fluctuations in pressure due to the intermittent discharge were sufficient to prevent the liquid flowing down 75 from tray to tray. Therefore, in order to reduce the fluctuations of pressure within the preliminary tray section, expansion chambers 19 and 20 were provided with orifices at 21 and 22. The restrictions to flow, following chambers for accumulation of pressure, reduced the fluctuations 80 in pressure sufficiently to permit the liquid to flow down from tray to tray. These chambers 85 may be made an integral part of the rectifying column.

90 Leaving the uppermost tray, the vapor passes up through a large central tube 23 in the vaporizer section to the space under the dome 24. The vapor then passes down through a large number of small tubes 25 in the vaporizer section and 95 is partly condensed. The vapor portion leaves through pipe 26. The liquid portion passes through liquid sealed tubes 27 and flows down from tray to tray through the preliminary tray section. The interaction of the down flowing stream of liquid with the rising vapor bubbling through it in each tray results in the rising vapor containing more and more nitrogen as it rises from tray to tray. The proper number of trays are provided to produce nitrogen vapor, having the topmost tray about 99 percent pure. Selective liquefaction is avoided in the vaporizer section by having the vapor partially liquefy as it passes downward through the tubes therein, so 100 that a reflux liquid containing about 99 percent 105 nitrogen is returned to the bottom tray. The 110

nitrogen is produced. As this liquid passes downward from tray to tray, it takes up oxygen from the rising vapor until it finally contains about 35 percent oxygen by the time it reaches pot E. At some intermediate tray, the oxygen percentage will be about 21 percent as in atmospheric air. As near this point as practicable, the liquefied air from liquefier C will be introduced through pipe 28 as determined by the control of valve 29.

10 The oxygen-rich liquid from pot E is throttled through pipe 30 by means of valve 31. This liquid enters the main tray section at 32 and overflows from tray to tray until it reaches the space above dome 24. From this space the liquid flows through pipe 33 to the space surrounding the tubes in the vaporizer, entering at a point about one-third the height of this section above its bottom point. The liquid will boil by heat transfer from the condensing vapor within the tubes and the resulting vapor will rise and leave the vaporizer section through pipe 34, entering the main tray section somewhat above the dome 24. The vapor will bubble through the downflowing liquid on the trays until it reaches the inlet tray at 32. 20 Here it will be joined by any vapor formed by throttling the oxygen-rich liquid and the total vapor will pass up through the trays above the inlet until it reaches the top tube section. In passing through the tubes in this section, the vapor will be partly liquefied, the vapor fraction passing out through pipe 35 while the liquid fraction returns as a reflux liquid through the trays above the inlet to the main tray section and joins the oxygen-rich liquid admitted at 32.

30 35 The vaporizer and top tube sections thus produces refluxes of vapor and liquid respectively through the trays of the main tray section. The interaction between the rising vapor stream and the downflowing liquid stream results in the oxygen-nitrogen mixture throttled into the main tray section being separated into nearly pure nitrogen vapor, say 99 percent pure, and nearly pure oxygen liquid, say 95 per cent pure.

40 The oxygen-rich liquid entering the vaporizer section through pipe 33 is fractionated by boiling so that a portion of this liquid leaving through pipe 36 is of higher purity than the entering liquid. It is for this reason that pipe 33 is connected to a point some distance above the bottom of the vaporizer section in order to minimize mixture of the less pure entering oxygen liquid with the purer oxygen liquid leaving through pipe 36. Pipe 36 is connected to exchanger K at a point somewhat above the bottom. In exchanger K, further fractionation occurs by boiling of the liquid in condensing a portion of the nitrogen vapor discharged from the preliminary tray section through pipe 26.

45 50 The remaining oxygen liquid passes through pipe 37 containing valve 38 into exchanger L where it is completely vaporized. Most of the vapor formed passes through pipe 39 to liquefier C. Part of the vapor passes through pipe 40 into exchanger K. The vapor formed in exchanger K, and that entering through pipe 40 are discharged through pipe 41 to augment the vapor reflux in the main tray section.

55 60 In passing down through the tubes in exchanger K, the nitrogen entering from pipe 26 is partly liquefied. The mingled liquid and vapor pass through pipe 42 to the pot 43 at the lower end of exchanger L. The vapor passes upward through the tubes in exchanger L, where it is nearly all liquefied, the liquefied portion flowing back into pot 43. The nitrogen liquid collect-

ing in pot 43 is throttled by valve 44 through pipes 45 and 46 into the top tube section of the rectifying column. Here the nitrogen liquid is vaporized by imparting refrigeration to produce a reflux liquid in the main tray section, and the vapor passes through pipe 47 to the liquefier C.

65 70 The gas remaining after the liquefaction of nearly all the nitrogen from the preliminary rectification, contains large portions of neon, hydrogen, helium and other highly volatile gases in the original atmospheric air compressed and cooled. This gaseous mixture is further purified in the purifier M by bringing it into heat exchange relation with the liquid nitrogen after being throttled to a lower pressure through valve 44. It had been previously in heat exchange with liquid oxygen which vaporizes at an appreciably higher temperature under the same pressure. The more volatile gases are further purified of nitrogen which is liquefied and separated in pot 48, returning to pot 43, through pipe 49. The purified rare gases are recovered through pipe 50 containing valve 51. In large plants, the refrigeration corresponding to the low temperature of these volatile gases may be utilized by returning these gases through the liquefier and inter-changers.

75 80 Instead of throttling the liquid air from liquefier C by valve 29 through pipe 28 into the preliminary tray section, this liquid air may be throttled by valve 52 through pipe 53, into the main tray section, the entering point being so selected that the composition of the liquid on the tray at that point is about the composition of the liquid admitted.

85 90 A by-pass valve 54 is provided between the expansion engine exhaust pipe 18 and the return pipe 47 from the top tube section J to the liquefier C.

95 100 Liquid level gages are provided as follows to indicate the liquid levels at the various points where liquids can accumulate, namely, 55 on bottom pot E, 56 on vaporizer G, 57 on exchanger L, 58 on pot 43, and 59 on top tube section J.

105 110 Two automatic regulators are provided to maintain constant the desired conditions of operation. One of these is an automatic pressure relief valve N on the discharge pipe for the nitrogen from the rectifier top. The control pipe 60 may be connected to the rectifier top as shown, to the bottom of the main tray section, to the vaporizer section, or to one of the exchangers. The other automatic device comprises an orifice O and a valve P controlled by the differential pressure across the orifice. This device is mounted in the oxygen discharge pipe.

115 120 The peculiar advantages of the process and arrangement shown will be brought out in describing the cooling down to operating temperatures and the normal operation.

125 130 A certain length of time will be required to cool down the apparatus to operating temperatures. Before starting the compressor, by-pass valve 54 is opened. Valve 38 should also be open and valves 31 and 44 may be open. Valves 29 and 52 should be closed. Valves 2, 5, 7, 12, 13 and 14 may be open while valves 3, 4, 6, 9, 10 and 11 may be closed to have the compressed air pass through interchanger A before passing through interchanger B.

135 140 The air compressor is then started and the compressed air passed into inlet 1 after being freed of carbon dioxide either before or after being compressed. As soon as the compressed air attains sufficient pressure, expansion engine D is 145 150

started. Most, if not all of the air after expansion passes through by-pass valve 54 and returns through the liquefier C and the interchanger B. By expansion, the temperature of the compressed air is reduced and the cooled returning air cools the liquefier C and interchanger B. The temperatures quickly drop until liquid air temperature under the compressed air pressure is reached in liquefier C. Liquid air then accumulates as indicated by level gage 17.

The liquid air in liquefier C is first throttled through valve 29 into the trays of the preliminary tray section F. Overflowing from tray to tray, this liquid air cools the preliminary tray section and liquid finally accumulates in pot E, as shown on level gage 55. The vapor rising from the liquid air passes through pipe 26 to start cooling the exchangers K and L and the top tube section J of the rectifying column.

When some liquid has accumulated in pot E, valve 29 is partly closed and valve 52 partly opened to supply liquid air to the trays of the main tray section H. As the trays fill with liquid it overflows from tray to tray and finally accumulates in vaporizer section G and exchangers K and L. The accumulated liquid will be indicated on level gages 56 and 57.

After considerable accumulation of liquid has occurred, valve 54 is gradually closed to get the plant into normal operation. The advantage of by-pass valve 54 is that by opening it, liquefier C and interchangers A and B act as an air liquefaction plant and quickly reach operating temperatures instead of cooling very slowly while cooling down the mass of metal in the rectifying column. Consequently, but little moisture is carried into parts of the system where it is frozen and cannot be removed during normal operation. The rectifying column and exchangers are cooled by liquid air only which has been freed of moisture. This conduces to longer operation of the plant as a whole before it becomes necessary to shut down and thaw out to remove accumulated ice.

Another advantage of the by-pass is that the expansion engine may be operated during cooling down with a lower back pressure than if it were necessary for the exhaust to pass through the rectifying column. This increases the refrigeration available during cooling down so that the cooling down period is shorter than if the by-pass were not provided.

The provision of both valves 29 and 52 is of great advantage in cooling down because it is thereby possible to fill many of the trays and accumulate liquid in both the preliminary and main tray sections without closing by-pass 54. Without valve 52, for example, it was found necessary to partly close valve 54 in order to raise the pressure in the preliminary tray section sufficiently to force liquid from pot E through pipe 30 and valve 31 into the main tray section. The provision of valve 52 increases the amount of refrigeration available during cooling down and thus reduces the length of the cooling down period.

When valve 54 is closed, the pressure in the preliminary tray section rises until liquefaction begins within the tubes of vaporizer G and exchangers K and L due to imparting heat to boil the liquid outside of these tubes. Equilibrium is finally reached where the heat transfer is just sufficient to liquefy all the air entering from the expansion engine, with the exception of that discharged by valve 51.

The liquid accumulating in the pot at the bot-

tom of exchanger L is throttled through pipe 45 and valve 44 into top tube section J of the rectifying column. Here the liquid vaporizes around the tubes in condensing vapor rising within the tubes. Very soon the normal refluxes are set up and the plant reaches steady operation.

During steady normal operation, the height of liquid in top tube section J will depend upon the temperature difference available for heat transfer between the nitrogen vapor condensing within the tubes and the nitrogen liquid vaporizing around the tubes. This temperature difference will, in turn, depend upon the rectification pressure (at the rectifier top) and the pressure under which the nitrogen liquid vaporizes. The latter pressure will depend upon the resistance encountered by the nitrogen upon returning through liquefier C and interchanger B and connecting piping. The rectification pressure will be determined by the adjustment of automatic pressure relief valve N. The adjustment of this valve may be changed until the height of liquid in the top tube section J is any desired amount. It is desirable to operate at as high a level as possible in order to utilize to the greatest advantage the surface available and reduce the rectification pressure to a minimum value.

There will be occasions when it will be desirable to dispense with the top tube section and dump the liquid nitrogen from pipe 46 directly into the main tray section. This will simplify the construction of the heads of liquefier C and interchangers A and B and of the return piping. The automatic pressure valve N may still be used, however, to govern the pressure of rectification in the main rectifier.

During steady normal operation, the automatic pressure reducing valve P will be set to give a flow through orifice O such as to produce the desired purities of the oxygen and nitrogen from the main tray section. If the flow is too large, the oxygen purity will be lower and the nitrogen purity higher than desired. If the flow is too small, the reverse will be true.

The liquid in pot E will be throttled through valve 31 as fast as it accumulates so as to maintain a nearly constant indication on liquid level gage 55.

As operation continues, solid particles of oil from the compressors and other impurities gather in the liquid oxygen in vaporizer G. These impurities are carried by the flow through pipe 36 into exchanger K and from thence through pipe 37 into exchanger L where they accumulate. At intervals, valve 38 may be closed and the liquid in exchanger L permitted to partially evaporate. Then the remaining liquid may be discharged through a drain pipe provided for that purpose, thereby carrying out of the system these accumulated impurities with minimum loss of oxygen liquid. Plants heretofore built have including no space which could be shut off at will and drained. It was, therefore, impossible to remove the accumulated impurities without seriously affecting the operation of the plant by removing a very large quantity of oxygen liquid.

The amount of heating surface provided in exchanger L is larger in comparison with the heating surface provided in vaporizer G and exchanger K than would correspond to the amount of heat required to vaporize the quantity of oxygen to be withdrawn from the plant. Consequently some excess vapor is always passing through pipe 40 from exchanger L to exchanger K. The oxygen vapor withdrawn through pipe 39 is, there-

fore, not contaminated with any vapor from exchanger K produced from the less pure oxygen liquid therein.

As the amount of heating surface in the two exchangers K and L approximately equals the amount of surface provided in vaporizer G, the two exchangers make a more compact apparatus than a single exchanger would. A single exchanger may be used, however, to liquefy the nitrogen vapor withdrawn in the preliminary rectification.

Valve 51 is opened to maintain such a flow through it as will prevent the accumulation of highly volatile gases from reducing appreciably the heat transfer in exchange L.

After some hours of operation, interchanger B will have its effectiveness reduced due to accumulation of ice formed from moisture in the compressed air. Valves 2, 3, 4, 5, 6, 7, 9, 10, 11, 12, 13 and 14 may then be reversed. The returning oxygen and nitrogen will then pass through interchanger A instead of interchanger B and the compressed air will just pass through interchanger B before passing through interchanger A when it will be cooled by the returning oxygen and nitrogen. In passing through interchanger B, the warm compressed air will thaw out the accumulated ice. The resulting water will move down into pot R from which it may be blown out through valve 61.

While the plant may be operated by throttling the liquid air from liquefier C either through valve 29 into the preliminary tray section F or through valve 52 into the main tray section H, there are certain advantages to the latter method of operation. Any change in the rate of supply of liquid air then affects conditions in the main tray section only, rather than in both the preliminary and main tray sections. The position of valve 31 does not have to be changed due to change in the flow from pot E. The liquid air helps in separating the nitrogen in the final rectification.

I claim:—

1. In apparatus for separating mixed gases, interchangers, a liquefier and expansion engine each connected to receive compressed air from the interchangers, a rectifying column having a preliminary tray section and a main tray section, means for introducing the exhaust of the expansion engine to the lower portion of the preliminary tray section, and means for introducing the liquid produced in the liquefier to either the said section or the main tray section or both.

2. In apparatus for separating mixed gases, interchangers, a rectifying column, an interposed liquefier connected to receive compressed gas from the interchangers and having return tubes connected to receive gases from the rectifier and to deliver gases to the return tubes of the interchangers, an expansion engine also connected to receive compressed gas from the interchangers, an outlet line from the engine to the rectifier, and a by-pass connecting the outlet line to return tubes of the liquefier.

3. In apparatus for separating mixed gases, interchangers, a rectifying column, an interposed liquefier connected to receive compressed gas from the interchangers and having return tubes connected to receive gases from the rectifier and to deliver gases to the return tubes of the interchangers, an expansion engine connected to receive compressed gas and to deliver gas to the rectifier, and means whereby the interchangers, the liquefier and the expansion engine may be

operated to bring about operating temperatures therein without cooling down the rectifier.

4. In apparatus for separating mixed gases, interchangers, a liquefier and expansion engine each connected to receive compressed air from the interchangers, a rectifying column having a preliminary tray section and a main tray section, means for introducing the exhaust of the expansion engine to the lower portion of the preliminary tray section, means for introducing the oxygen rich mixture produced in the preliminary tray section to the main tray section, and means for introducing the liquid produced in the liquefier to the main tray section at a point above the inlet of the oxygen rich mixture to the main tray section but substantially below the top of said section and where the composition of the liquid on the trays is substantially the same as the liquid so introduced.

5. In apparatus for separating mixed gases, interchangers, a rectifying column, an interposed liquefier connected to receive compressed gas from the interchangers and having return tubes connected to receive gases from the rectifier and to deliver gases to the return tubes of the interchangers, an expansion engine, an inlet line from the interchangers to the expansion engine, an outlet line from the engine to the rectifier, and a by-pass connecting the outlet line to the return tubes of the liquefier, the column having a preliminary tray section and a main tray section, and means for introducing the liquid produced in the liquefier to the tray sections.

6. In apparatus for separating mixed gases including interchangers, a rectifying column, an interposed liquefier connected to receive compressed gases from the interchangers and having return tubes connected to receive gases from the rectifier and to deliver gases to the return tubes of the interchangers, an expansion engine connected to receive compressed gas and to deliver gas to the column, means whereby the interchangers, liquefier and expansion engine may be operated to bring about operating temperatures therein without cooling down the rectifier and means introducing liquid produced in the liquefier to the column.

7. In apparatus for separating mixed gases, interchangers, a rectifying column, an interposed liquefier connected to receive compressed gases from the interchangers and having return tubes connected to receive gases from the column and to deliver gases to the return tubes of the interchangers, an expansion engine, an inlet line from the interchangers to the engine, an outlet line from the engine to the rectifier, a by-pass connecting the outlet line to the return tubes of the liquefier and a valve in the by-pass.

8. In apparatus for separating mixed gases, interchangers, a rectifying column, an interposed liquefier connected to receive compressed gases from the interchangers and having return tubes connected to receive gases from the column and to deliver gases to the return tubes of the interchangers, said column having a preliminary tray section and a main tray section, an expansion engine, an inlet line from the interchangers to the expansion engine, an outlet line from the engine to the preliminary tray section of the column, means for introducing liquid produced in the preliminary tray section to the main tray section, an expansion chamber in said outlet line, said outlet line being provided with an orifice intermediate said chamber and the column.

WILLIAM L. DE BAUFRE. 150
